(57) **CLAIM**

The ornamental design for an axial piston machine as shown and described.

DESCRIPTION

FIG. 1 is a perspective view of an axial piston machine showing a first embodiment of our new design;

FIG. 2 is a right side elevational view of the axial piston machine of FIG. 1;

FIG. 3 is a left side elevational view of the axial piston machine of FIG. 1;

FIG. 4 is a rear side elevational view of the axial piston machine of FIG. 1;

FIG. 5 is a front side elevational view of the axial piston machine of FIG. 1;

FIG. 6 is a top plan view of the axial piston machine of FIG. 1; and

FIG. 7 is a bottom plan view of the axial piston machine of FIG. 1.

FIG. 8 is a perspective view of an axial piston machine showing a second embodiment of our new design;

FIG. 9 is a right side elevational view of the axial piston machine of FIG. 8;

FIG. 10 is a left side elevational view of the axial piston machine of FIG. 8;

FIG. 11 is a rear side elevational view of the axial piston machine of FIG. 8;

FIG. 12 is a front side elevational view of the axial piston machine of FIG. 8;

FIG. 13 is a top plan view of the axial piston machine of FIG. 8; and,

FIG. 14 is a bottom plan view of the axial piston machine of FIG. 8.

(Continued)

The broken lines shown in the drawings depict portions of the axial piston machine that form no part of the claimed design.
